UNITED STATES PATENT OFFICE.

GASTON E. CONSTANTIN, OF BROOKLYN, NEW YORK.

DESIGN FOR A BICYCLE-COVER.

SPECIFICATION forming part of Design No. 25,879, dated August 4, 1896.

Application filed June 10, 1896. Serial No. 595,035. Term of patent 7 years.

To all whom it may concern:

Be it known that I, GASTON E. CONSTANTIN, a citizen of the United States, residing at Brooklyn, in the county of Kings and State of New York, have invented and produced a new and original Design for a Bicycle-Cover, of which the following is a specification, reference being had to the accompanying drawings, forming a part thereof, in which—

10 Figure 1 is a perspective view of a cover embodying my design viewed from the side, and Fig. 2 is a plan view of the said cover.

In general contour the cover approximates the shape of a liberty-cap.

15 The top A of the cover appears as a flat surface transversely throughout the major portion of its length, and the aforesaid top gradually increases in width from its rear

end to a point near its forward end, and the side edges of the said top meet at both extremities. The meeting edges of the cover are merged into the front and rear central lines B and B' of the aforesaid cover, and both of these front and rear lines B and B' partake of the shape of a compound curve; 25 but the leading feature of the design consists in a cover which approximates in general contour the shape of a liberty-cap.

I claim—

The design for a bicycle-cover, substantially as herein shown and described.

GASTON E. CONSTANTIN.
